UNITED STATES PATENT OFFICE.

WILLIAM PEARCE, OF PLANTSVILLE, CONNECTICUT, ASSIGNOR OF TWO-THIRDS TO MERRITT N. WOODRUFF AND NORMAN A. BARNES, OF PLANTSVILLE, CONNECTICUT.

NAIL-PULLER.

SPECIFICATION forming part of Letters Patent No. 700,440, dated May 20, 1902.

Application filed August 31, 1901. Serial No. 73,975. (No model.)

To all whom it may concern:

Be it known that I, WILLIAM PEARCE, of Plantsville, in the county of Hartford and State of Connecticut, have invented a new and useful Improvement in Nail-Pullers; and I do hereby declare the following, when taken in connection with the accompanying drawings and the letters of reference marked thereon, to be a full, clear, and exact description of the same, and which said drawings constitute part of this specification, and represent, in—

Figure 1, a view in side elevation of a nail-puller constructed in accordance with my invention; Fig. 2, an enlarged view, in transverse section, on the line *a b*; Fig. 3, a detached view, in side elevation, of the foot; Fig. 4, a view of the foot in front elevation.

My invention relates to an improvement in nail-pullers, the object being to produce a simple, compact, convenient, and effective puller constructed with particular reference to fewness of parts, durability, and lightness.

With these ends in view my invention consists in a nail-puller having certain details of construction and combinations of parts, as will be hereinafter described, and particularly recited in the claim.

In carrying out my invention as herein shown I employ two plates 2 2, corresponding to each other and rounded at their forward and rear ends and tapering from front to rear. These plates are rigidly secured at their forward ends by rivets 3 or otherwise to the opposite faces of the forward jaw 4 and extend rearward beyond the rear or outer edge of the rear jaw 5, which is free to move back and forth between them. Preferably two or more rivets will be employed to secure the plates to the forward jaw, so that they cannot possibly turn thereon. Their projecting rear ends receive a bolt 6, having a nut 7, upon which the foot 8 swings. The upper or inner end of this foot is shaped to form a cam 9, the extremity of which is cut away to form a groove 10, which conforms to the rounded rear or cammed outer edge 11 of the rear jaw 5, the said cam coacting with the convex outer edge of the jaw at a point above the

greatest convexity thereof. The parts described are constructed and combined so that the jaws are brought together and the nail seized after the handle 12 of the nail-puller has been moved through a very short arc. This is obviously advantageous, as it pulls the nail straighter and with less effort than if it were necessary to swing the entire nail-puller for a longer distance for the gripping of the nail. When the cam 9 has forced the jaw 5 toward the jaw 4, the groove 10 of the cam 60 fits over the convex face 11 of the jaw 5, whereby the jaw and cam are interlocked against the lateral movement.

The foot 8 is made so nearly straight that the action of the puller is substantially a lifting action from the end of the foot instead of a rolling action beginning at or near the middle of the foot and then extending outward to the end thereof, as in many prior constructions. The coaction of the cam 9 with the convex outer edge 11 of the jaw 5 at a point above the greatest convexity of the said edge causes the cam to force the jaw downward under the nail, whereas in some nail-pullers the construction is just the opposite, the tendency being exerted to lift the nail-puller away from the nail.

It will be seen from the foregoing that the foot 8 of my improved device is constructed with particular reference to acting through its extreme ends on the floor at its extreme lower end and on the movable jaw at its extreme upper end rather than between its ends through a long convex inner edge, as heretofore used. This results in the very substantial advantages already set forth of reducing the bending of the nails to the minimum in pulling them and in driving the movable jaw downward under the nails preparatory to gripping them.

It is apparent that in carrying out my invention some changes in the construction herein shown and described may be made. I would therefore have it understood that I do not limit myself to the said construction, but hold myself at liberty to make such variations therefrom as fairly fall within the spirit and scope of my invention. I am aware, however,

that nail-pullers have been constructed with two plates riveted to one jaw and extending rearward beyond the other jaw, with a foot pivotally mounted between the projecting ends of the plates, and therefore do not wish to be understood as claiming, broadly, such as my invention.

Having fully described my invention, what I claim as new, and desire to secure by Letters 10 Patent, is—

In a nail-puller, the combination with the rear and forward jaws thereof, the outer edge of the rear jaw being convex, of two plates rigidly secured by their forward ends to the 15 opposite faces of the forward jaw and extending rearwardly beyond the outer edge of the rear jaw which is free to move between them, a pivot passing through the projecting rear

ends of the plates, and a foot hung upon the said pivot and shaped to act at its ends rather than between the same, its upper end being formed with a cam coacting with the said convex outer edge of the rear jaw at a point above the greatest convexity thereof to force the said jaw downward under the nail, as well as 20 inward toward the other jaw, and the lower end of the said foot constituting a fulcrum upon which the entire device turns as upon a center.

In testimony whereof I have signed this 30 specification in the presence of two subscribing witnesses.

WILLIAM PEARCE.
